UNITED STATES PATENT OFFICE.

RUDOLF ROSENKRANZ, OF PITTSBURG, PENNSYLVANIA.

ARTIFICIAL LIMB.

No. 817,340.

Specification of Letters Patent.

Patented April 10, 1906.

Application filed March 1, 1905. Serial No. 247,856.

To all whom it may concern:

Be it known that I, RUDOLF ROSENKRANZ, a citizen of the United States, residing at Pittsburgh, in the State of Pennsylvania, have 5 invented certain new and useful Improvements in Artificial Limbs, of which the following is a specification.

My invention relates to artificial legs and especially to the joint connecting the leg and the foot. The objects of the invention are, to provide a superior universal joint between the main part of the artificial leg and its lower extremity; to provide a joint which will closely simulate in action the natural joint 15 of the ankle; to avoid jar upon the stump when the limb is brought in contact with the ground, and to simplify and to strengthen and generally improve the construction of artificial limbs. These objects and other advantages which will hereinafter appear, I attain by means of the construction illustrated in preferred forms in the accompanying drawing wherein—

Figure 1 is a central vertical section through 25 an artificial leg and foot having my improvement;

Figures 2 and 3 are respectively, a central longitudinal section, and a plan view, of the cushion member of the joint showing an alternate construction of the cushion, and

Figure 4 is a central section of a modified form of the limb for use when the foot must be directly joined to the lower end of the artificial leg.

Primarily I avoid the use of hinges and sliding parts in the joint by providing a cushion or compression member between the foot and the lower part of the leg, and connect the parts for universal movement by means of a ball-and-socket joint. In the form of the device shown in Figure 1, it will be seen that the foot portion 5 is connected to the leg portion 6 by means of the bolt or rod 7 which is inclosed preferably in a non-metallic sheath 8, and the connected parts are separated by the intermediate resistance of the cushion block 9 which is preferably made of rubber. The bolt 7 extends through this cushion block and has a spherical head which works in a 40 socket formed by two semi-spherical plates 11 and 11^a both of which are screwed to the foot portion 5. In the socket may be provided some pockets of graphite 12, or other lubricating material, and the rubber cushion 50 block 9 is maintained in position by means of pins

13 fixed in the flat faces of the two wooden portions 5 and 6.

The cushion block 9 has at its forward side a portion 9^a which is of denser structure of rubber so as to provide greater resistance 60 when the pressure comes upon this portion by the tilting forward of the leg portion 6 with respect to the foot portion 5, so that as the tilting proceeds the resistance becomes greater and greater in order to simulate the 65 natural action of the foot as much as possible and make the joint most resilient at the rear. The bolt 7 ordinarily is not required to move at all since the cushion-block 9 allows for all variations of distance between the surfaces of 70 the leg portion and the foot portion, the leg moving about the ball 10 as a center. The bolt 7 may be kept tight and noise avoided by use of a rubber washer 14 placed under the lock nut at the top as shown.

In Figures 2 and 3 is shown an alternate construction of the cushion block 9 in which the greater resistance necessary in the forward portion is provided by an inserted block 15 of harder rubber than the remainder 80 of the body, having the same effect as the denser portion 9^a in the first form described.

In Figure 4 is shown a modification of the devices adapted to the use of such limbs designed to accommodate legs cut off at the ankle, or just above, in which case there is not much room in the leg portion to fix the bolt 7 and it is therefore inverted and the socket is placed on the upper side of the cushion block 9. As shown, the leg part 22 has at the bottom a plate 19 through which pass some rivets 20, holding the two plates 17 and 18 which are used to form the socket for the head of the bolt. In this case also the bolt 7 is secured by a lock nut and underneath it 95 there is a cushion of rubber 21 in the portion 5, as in the first instance.

It will be seen that by this construction the foot portion has a universal joint with the leg portion so that it may tilt laterally, 100 and move forward and back, and in either motion it is resisted by the resiliency of the rubber block 9; also that in the ordinary tilting motion of the leg in walking, the block 9 provides a heavier resistance on the front 105 than on the back and this resistance will increase in greater ratio by reason of the denser structure of the rubber between the two forward surfaces of the leg portion 6 and the foot 5. Since the bolt 7 does not have any 110

sliding motion in its sheath it is not required to be lubricated and is entirely out of contact with any portion which might make noise, being surrounded by a leather tube 8 and 5 resting on the rubber washer, which also maintains a snug fit of the ball 10 in its socket 12. It will be seen also that there are no parts which can get out of order as the parts are all held in proper position by the 10 weight upon the limb, and there are no moving parts except the revolution of the ball 10 in its socket and this cannot make any noise and requires only the lubrication that can be supplied by the graphite inserts therein. It 15 will also be seen that the parts are readily assembled or can be taken apart or can be easily interchanged, and the resistance of the joint to bending can be regulated by varying the amount of the dense portion of the rubber. In any motion of the foot the entire effect of weight of the leg is met with a resilient cushion and all jarring is avoided. Other 20 advantage of the structure will readily occur to those familiar with the art.

25 Having thus described my invention and illustrated its use, what I claim as new, and desire to secure by Letters Patent, is the following:

1. An artificial limb comprising a leg portion and a foot portion and an intermediate rubber portion continuous in outer contour with the other two said portions and entirely separating them, and a universal ball-and-socket joint connecting the two solid portions by parts passing through the rubber portion, substantially as described.
2. In an artificial leg the combination with a leg portion and a foot portion, and connecting means to hold them together each portion having a flat joint surface, of a rubber cushion between said portions extending over the entire area of said flat surfaces and

being flush with the outline of the foot on the outside and forming part of the contour, said rubber cushion having an integral part more 45 dense than the rest, at the forward side, substantially as and for the purpose described.

3. In an artificial leg the combination with a leg portion having a flat end, a foot portion having a flat top, a rubber cushion between two said parts extending over the entire area 50 of said flat portions and its outer surfaces continuous with the outline of the foot, a rod fixed in the leg portion, extending through the said rubber portion, a ball on the same 55 and an engaging socket on the foot portion, said rubber cushion having the forward end made of denser rubber than the rest, to afford greater resistance to compression, substantially as described.

4. An artificial leg having a leg portion and a foot portion of solid material, an intervening block of rubber entirely covering the surfaces of said portions and being continuous with the other parts in outline, whereby 65 there is no moving joint between the foot and leg portion, and a non-metallic sheath and a rod therein having a head making a universal joint between the foot and leg portions allowing free compression of said rubber pad, substantially as described.

5. In an artificial limb a cushion for spacing apart the foot and leg portions composed of soft rubber which has an integral forward part of it made more dense than the rest to 75 afford greater resistance at the forward side of the foot, substantially as described.

In testimony whereof I have hereunto signed my name in the presence of the two subscribed witnesses.

RUDOLF ROSENKRANZ.
